UNITED STATES PATENT OFFICE.

JAMES M. CLEM, OF OPELIKA, ALABAMA, ASSIGNOR OF PART OF HIS RIGHT
TO WILLIAM D. CONDON, GEO. A. BIRCH, ALEXANDER P. BIRCH, AND W.
B. SHAPARD & CO., OF SAME PLACE.

IMPROVEMENT IN RAILWAY-RAIL JOINTS.

Specification forming part of Letters Patent No. 149,722, dated April 14, 1874; application filed
February 21, 1874.

To all whom it may concern:

Be it known that I, JAMES M. CLEM, of Opelika, in the county of Lee and State of Alabama, have invented a new and valuable Improvement in Locks for Railroad-Rails; and I do hereby declare that the following is a full, clear, and exact description of the construction and operation of the same, reference being had to the annexed drawings making a part of this specification, and to the letters and figures of reference marked thereon.

Figure 1 of the drawing is a representation of a sectional view of my device. Fig. 2 is a plan view of the same. Fig. 3 is a detail view of the same.

This invention has relation to means for locking down railroad-spikes so that they will not work loose; and it consists in combining with the broad-slotted bolts (through which the spikes are driven for the purpose of clamping splicing-bars to the rails at their joints) angular locking-plates, the angular portions of which are received into the slots through the said bolts and splice-bars, and the upper ends of which are bent down over the spike-heads after the spikes are driven home, as will be hereinafter explained.

The following is a description of my improved locking device:

In the annexed drawings, A designates a railroad-rail, of the T shape; B B', splicing or fish bars, which are applied between the lips of the rail-head and the base flanges, and which break joints with the ends of the rail sections. The splicing-bars and the webs of the rails have oblong holes through them, through which bolts C are passed. Bolts C have heads on their inner ends, and oblong

slots through their outer ends, through which latter spikes D are driven, that pass through the base flanges of the rail sections and into the cross-tie. G designates a strip of metal, of suitable length and thickness, and of a width nearly equal to the width of the slots through the bolts C. This strip is bent by suitable dies, so as to leave a rectangular portion, g, midway of its length. Before driving the spikes D one or more of the locking-plates G is adjusted against the outside and thickest splicing-plate B, the angular portion g being inserted into the oblong hole through this plate, as shown in Fig. 1. When the spike is driven through the bolt C, through the bottom flange of the rail, and into the cross-tie, the locking strip or strips G will be firmly confined between the spike and splicing-bar B, such strip or strips G being held down by reason of the angular portion g entering the hole in the bar B, as above described. When the spike is driven home, the upper end of the strip G is bent over the head of the spike, as shown at g', thus effectually preventing the spike from rising or working loose.

What I claim as new, and desire to secure by Letters Patent, is—

The rail-spike lock, consisting of a metal strip bent at g, and adapted for use in connection with flat-slotted bolts C, fish-plates B B', and spikes D, as and for the purposes described.

In testimony that I claim the above I have hereunto subscribed my name in the presence of two witnesses.

JAMES M. CLEM.
